DESIGN FOR A COMBINATION KITCHEN STOOL AND STEPLADDER

Charles E. Morley, Detroit, Mich.

Application February 12, 1944, Serial No. 112,570

Term of patent 14 years

(Cl. D15—8)

To all whom it may concern:

Be it known that I, Charles E. Morley, a citizen of the United States, residing at Detroit, in the county of Wayne and State of Michigan, have invented a new, original, and ornamental Design for a Combination Kitchen Stool and Stepladder, of which the following is a specification, reference being had to the accompanying drawing, forming part thereof.

Figure 1 is a perspective view of the combination kitchen stool and stepladder, showing my design in its extended position; and

Figure 2 is a perspective view thereof, in its collapsed position.

Figure 3 is a top plan view of Figure 1.

Figure 4 is an enlarged fragmentary sectional view taken along line 4—4 of Figure 3 and in the direction of the arrows.

I claim:

The ornamental design for a combination kitchen stool and stepladder, as shown and described.

CHARLES E. MORLEY.
